UNITED STATES PATENT OFFICE.

SAMUEL P. KAY, OF ROCHESTER, NEW YORK, ASSIGNOR OF ONE-HALF TO ANNIE K. ROWND AND ONE-HALF TO ARETHUSA KAY, BOTH OF ROCHESTER, NEW YORK.

PENCIL-HOLDER.

1,338,933.

Specification of Letters Patent. Patented May 4, 1920.

Application filed August 18, 1919. Serial No. 318,283.

To all whom it may concern:

Be it known that I, SAMUEL P. KAY, a citizen of the United States, residing at Rochester, in the county of Monroe and State of New York, have invented certain new and useful Improvements in Pencil-Holders, of which the following is a specification.

The object of this invention is to provide a new and improved pencil holder which can be permanently fastened into the pocket and the pencil inserted therein and taken out therefrom without danger of breaking the pencil point.

This and other objects of this invention will be fully illustrated in the drawings, described in the specification and pointed out in the claims at the end thereof.

In the accompanying drawings: Figure 1 is a side elevation of the pencil holder.

Fig. 2 is a longitudinal section of the holder, the section being taken on the line 2^x-2^x of Figs. 1 and 4.

Fig. 3 is a cross section of the pencil holder, the section being taken on the line 3^x-3^x of Fig. 2.

Fig. 4 is an end elevation of the pencil holder.

Fig. 5 is a sectional view of a modified form of the pencil holder.

In the several figures of the drawing, like reference numerals indicate like parts.

The pencil holder forming the subject matter of this invention comprises the metal tube 1, which has one end thereof slightly closed as indicated at 2 in Figs. 1 and 2. The other end of the tube is split into preferably the three sections 3, 4 and 5. Each of these sections extends toward the rear end of the pencil holder about one third of the full length thereof and is separated from the other by the slots 6, 7 and 8 respectively.

The sections 3, 4 and 5 form suitable spring members which are adapted to press against the outside of the pencil when inserted between them and thus operate to hold the pencil firmly in place in the holder.

The section or spring member 3 has an ex-

tension 9 provided thereon, which extension is turned back over the top of the section 3, leaving a small space between them. The extension 9 thus forms an additional spring member between which and the member 3 the edge of the pocket may be forced in order to support the holder securely on either the outside or inside of the pocket.

Near the partially closed end of the tube 1 are provided the four inwardly projecting prongs 10, 11, 12 and 13. These prongs are punched out of the sides or wall of the tube 1 and form an integral part therewith but leave triangular shaped openings in the tube at the point where the prongs have been bent inwardly. The prongs 10, 11, 12 and 13 are bent toward each other on the inside of the tube in order to leave a space of reduced diameter to that of the tube between them. In this way, these prongs form a stop against which the tapered end of the wooden part of the pencil abuts when the pencil is inserted into the holder. The pointed lead or graphite core of the pencil, however, is allowed to project between and beyond the prongs, but is held centrally thereof as shown in dotted lines in Fig. 2. The prongs 10, 11, 12 and 13 also act as small springs so that when the pencil point is forced against them on the insertion of the pencil into the holder, these prongs operate to hold the graphite core yieldingly suspended in the center of the tube near the partially closed end thereof.

A firm support for both the pencil body and the pencil point is thus secured which not only holds the pencil in place in the holder, but also insures the point thereof from breaking while in place in the holder.

In Fig. 5 is shown the tube 1 as having a rectangular cross section and it is understood that any other form of cross section may be used in connection with this invention.

I claim:

1. In a pencil holder, the combination of a tube, a series of spring lugs punched out of the wall of said tube and bent inwardly thereof, said lugs surrounding and forming

yielding stops for the pencil point of the pencil held centrally in place in said holder thereby.

2. In a pencil holder, the combination of
5 a tube, a series of spring lugs punched out
of the wall of said tube and bent inwardly
thereof, said lugs surrounding and forming
yielding stops for the pencil point of the

pencil held centrally in place in said holder thereby, the adjacent ends of said tube being 10
partially closed to protect the pencil point held suspended in place in said tube by said
spring lugs.

In testimony whereof I affix my signature.

SAMUEL P. KAY.
